UNITED STATES PATENT OFFICE.

WILLIAM W. BAUMAN, OF RITTMAN, OHIO.

CUT-OFF MECHANISM.

1,200,298.

Specification of Letters Patent. Patented Oct. 3, 1916.

Application filed April 8, 1914. Serial No. 830,464.

To all whom it may concern:

Be it known that I, WILLIAM W. BAUMAN, a citizen of the United States, residing at Rittman, in the county of Wayne, and 5 State of Ohio, have invented certain new and useful Improvements in Cut-Off Mechanism; and I do hereby declare the following to be a full, clear, and exact description of the invention, such as will enable 10 others skilled in the art to which it appertains to make and use the same.

This invention relates to new and useful improvements in devices for controlling the operation of lights, and has for its principal object to provide a device which is capable of automatically putting out lights at predetermined times.

Another object of the invention is to provide a device which is capable of automatically operating oil lights by which they may be extinguished without necessitating the use of manual labor in performing the operation.

Still another object of the invention is to 25 provide a novel means by which the device may be thrown out of operation when it is desired to operate the lights manually.

A further object of the invention is to provide a device in which the spring which 30 operates the mechanism is also used to force the drive wheel in contact with the wheels which are to be driven.

With these and other objects in view, the invention consists in the novel combination 35 and arrangement of parts which will be fully set forth in the following specification and accompanying drawings, in which,

Figure 1 is a side view in elevation of a lamp burner showing this improved device 40 as it would appear when applied thereto, Fig. 2 is a longitudinal sectional view of the device to clearly show the mechanism thereof, Fig. 3 is a rear view in elevation of a device showing the rear plate removed to 45 clearly show the interior mechanism of the device, Fig. 4 is a view of the rear plate in elevation showing the key as it would appear when the device is in its inoperative position, Fig. 5 is a view similar to Fig. 4 showing the key in its operative position, 50 Fig. 6 is a detail perspective view of the interior of the plate illustrated in Fig. 4, Fig. 7 is a detail view of the operating shaft showing the same as it would appear when 55 in position to operate the wheels controlling the wick of the lamp, and Fig. 8 is a

view illustrating the position of the key when the friction wheels which are driven thereby are in contact, and showing the device in its unwound position.

Referring now to the drawings by characters of reference, the numeral 1 designates as an entirety the casing of the device having the removable rear plate 2, which plate is provided intermediate its ends with the 60 inverted triangular opening 3 having the tongue 4 extending thereinto. An angular extension or lug 5 is formed on the tongue as clearly shown and is arranged to rest upon the strip 6 which extends transversely 65 of the plate and is bent as at 7 intermediate its ends and again bent as at 8 near each end to form the spacing members which hold the said strip in spaced relation to the plate. This lug 5 is arranged to form the stop 70 which limits the movement of the key when the device is in use. A centrally located aperture 9 is formed in the strip and is located slightly above the apex of the triangular opening 3 as clearly shown in Fig. 6. A 75 short longitudinal slot 10 is formed centrally between the lateral edges of the plate 2 and is arranged to form a guide for the friction wheel which will be more fully 80 hereinafter described.

Journaled within the casing 1 intermediate its ends is a shaft 11 which has secured thereto the friction wheel 13, having formed integrally therewith, a spur gear 12, which meshes with the gear wheel 14, which 85 is journaled upon the shaft 19. A spur gear 15 is formed integrally with the gear wheel 14 and rotates therewith upon the shaft 19. The spur gear 15 meshes with the gear wheel 16, which is journaled upon the shaft 11 and 90 has formed integrally therewith a spur gear 17. The spur gear 17 rotates with the gear wheel 16, and is in mesh with the gear wheel 18 which is secured to the shaft 19 by a lug 19' carried by the wheel 18 and fitting 95 into the slot 19^b in the shaft 19, as illustrated in Figs. 2 and 3. The lug 19' may be heated and bent at right angles to the plane of the gear 18 so as to permit the placing of the gear upon the shaft 19, after 100 which the lug may be bent into the slot 19^b, or the lug may be made separately and attached to the gear 18 and positioned into the slot 19^b after the gear has been placed upon the shaft 19. The shaft 19 is journaled in the bearing formed by the aperture 9 in the plate 6 and also journaled in 105 110

the bearing formed by the U-shaped member 20, which is riveted or otherwise secured as at 21 to the front wall of the casing 1.

The shaft 19, above referred to, is provided at one end with the friction wheel 22 which is arranged to rotate therewith. A suitable coil spring 23 surrounds the shaft between the bearing 20 and the friction wheel 22 and is secured respectively to the bearing and frictional wheel, so that when the shaft is rotated, the spring will have a tendency to force the shaft back into its normal position. Thus it will be seen that when the shaft is rotated, the several sets of gearing will set in operation, thus gradually turning down the light and finally extinguishing the same. The end of the shaft 19 opposite the end to which the friction wheel 22 is secured, is bent as at 24 and again bent to form the U-shaped member 25, one arm of which projects upwardly as at 26 and is bent back upon itself and terminates in the U-shaped member 27, the free end of the arm of which terminates in the angular projection 28, which is arranged to enter the aperture 29 formed in the projection 4 to hold the key in its inoperative position when so desired by the user.

A suitable slot 30 is formed in the front plate of the casing 1 and is arranged to register with the slot 10 formed in the plate 2. These slots are arranged to receive the ends of the shaft 31 upon which the friction wheel 32 is rotatably mounted. A U-shaped frame 33 is operatively connected with relation to the friction wheel 32, and has projecting upwardly therefrom the cylindrical threaded extension 34 which is surrounded by the coil spring 35, which coil spring is arranged to exert downward pressure against the U-shaped frame 33 so as to force the friction wheel 32 into frictional engagement with the friction disk 13 to retard the rotation of the gear wheels and thereby control the operation of the wheel 22. A suitable thumb screw 36 is adapted to coöperate with the threaded extension 34 to pull the frame 33 upwardly so that the compression of the friction wheel 32 on the friction disk 13 may be manually controlled.

It will be apparent from the foregoing that in use the wheel 22 is brought into operative relation with the friction wheels 37 which is best illustrated in Fig. 7, and it will be apparent that when the friction wheel 22 is rotated, the wheels 37 will be rotated correspondingly and the light which is to be controlled may be turned down and extinguished at a predetermined time. When the user desires to throw the device out of operation, the shaft 19 is pulled outwardly so that the friction wheel 22 disengages the friction wheels 37 and the extension 28 is brought into alinement with the aperture 29 in the extension 4 and allowed to project through

said extension, in which position the shaft will be held in inoperative relation with the friction wheels 37 and manual operation of the wheels may be resorted to without any interference from the controlling device.

When it is desired to put the device in operation, the shaft 19 is pulled outwardly to withdraw the lug 28 from the aperture 29, after which the shaft is turned in a clockwise direction to wind the spring 23. The shaft is then shoved inwardly to place the wheel 22 in operative engagement with the wheels 37 and to position the arm 28^a on the inside of the wall 2 against the left hand side of the lug 5 on the tongue 4. When the shaft is released, the spring 23 will in unwinding turn the shaft in a counter-clockwise direction. The movement of the shaft in this direction tends to gradually move the wick downwardly. When the shaft has been turned sufficiently to move the arm 28^a from an engagement with the left hand side of the lug 5 and into engagement with the right hand side of the lug, the wick will have been moved downwardly sufficiently to extinguish the lamp. The speed of the movement of the shaft may be regulated and controlled through the medium of the friction wheel 32, rendering it possible to extinguish the lamp in any predetermined time. The engagement of the arm 28^a against the right hand side of the lug 5, stops the operation of the device. The offset portion of the strip 6 permits the lug 28 to pass the strip during the movement of the shaft 19 by the spring 23. When it is desired to only turn the lamp down at a predetermined time, it is only necessary to limit the movement of the shaft 19 by the spring 23, and this may be done when setting the device and placing the arm 28^a in spaced relation to the left hand side of the lug 5. The gear 18 being keyed to the shaft 19 will rotate said shaft according to the rotation of the remaining train of gears and will prevent the gear 18 from being moved with and by the shaft during the inner and outer movements of the shaft 19 when setting or locking the device.

While in the foregoing there has been shown and described the preferred embodiment of this invention, it is to be understood that such changes may be made in the combination and arrangement of parts as will fall within the spirit and scope of the invention as defined in the appended claims.

Having thus described my invention, I claim:

1. In a device of the character described, a casing, a shaft mounted in said casing, a coil spring surrounding the shaft and adapted to rotate the same, a frictional wheel carried by one end of the shaft and arranged to control the operation of the lighting system, a key at the opposite end of the shaft and

adapted to provide means whereby the spring may be wound to set the device in action, means to lock the shaft in an inoperative position and prevent the shaft from rotating, and means to manually control the speed of rotation of the friction wheel whereby the operation of the lighting system is controlled.

2. In a device of the character described, 10 a casing, bearings secured to the rear and front walls of the casing, a shaft rotatably mounted in said bearings, one of said bearings being substantially U-shaped, a coil spring surrounding said shaft and adapted 15 to rotate the same, a friction wheel carried by one end of said shaft and arranged to control the operation of a lighting system, a key at the opposite end of the shaft and adapted to provide a means whereby the 20 spring may be wound to set the device in operation, said coil spring having one end bearing against said U-shaped bearing and the opposite end against said friction wheel whereby said friction wheel is normally held 25 in engagement with the lighting system operation control, means to move the shaft into an inoperative position and prevent the rotation of the same and means to control the speed of rotation of the friction wheel.
3. In a device of the character described, 30 a casing, bearings secured to the front and rear walls of the casing, said bearings being spaced from said walls and provided with alining apertures, the rear wall of the casing having an inverted triangular opening, the apex of which is located slightly below 35 the apertures in the bearings, a tongue formed on the rear plate and extending into said triangular opening and having a recess 40 in the central portion thereof, a projection on said tongue and extending into said casing, a shaft mounted in said apertures in 45 said bearings, a coil spring surrounding said shaft and adapted to rotate the same, a friction wheel carried by one end of the shaft and arranged to control the operation of the lighting system, a key at the opposite end of the shaft and adapted to provide a means whereby the spring may be wound to set the device in operation, an angular projection formed on the free end of said key and lying 50 vice in operation, an angular projection formed on the free end of said key and lying

in a plane parallel to the shaft, said projection being adapted to engage the projection on the tongue and thereby limit the rotation of the shaft, said spring having one 55 end bearing against one of said bearings and the opposite end against said friction wheel whereby said shaft is normally held in engagement with the lighting system operation control, and means to prevent the rotation 60 of the shaft and to manually control the speed of rotation of said shaft.

4. In a device of the character described, 65 a casing, bearings secured to the front and rear walls of the casing, said bearings being spaced from said walls and provided with alining apertures, the rear wall of the casing having an inverted triangular opening, the apex of which is located slightly below 70 the apertures in the bearings, a tongue 75 formed on the rear plate and extending into said triangular opening and having a recess in the central portion thereof, a projection on said tongue and extending into said casing, a shaft mounted in said apertures in 80 said bearings, a coil spring surrounding said shaft and adapted to rotate the same, a friction wheel carried by one end of the shaft and arranged to control the operation of the lighting system, a key at the opposite 85 end of the shaft and adapted to provide a means whereby the spring may be wound to set the device in operation, an angular projection formed on the free end of said key and lying in a plane parallel to the shaft, 90 said projection being adapted to engage the projection on the tongue and thereby limit the rotation of the shaft, said shaft being adapted to slide longitudinally and the projection on said key being adapted to engage 95 said recess in the tongue whereby said shaft is prevented from rotating and held in an inoperative position, and means to manually control the speed of the rotation of said shaft.

In testimony whereof I affix my signature in presence of two witnesses.

WILLIAM W. BAUMAN.
